UNITED STATES PATENT OFFICE

LOUIS WEISBERG, OF BRIGHTON BEACH, NEW YORK

CIGARETTE HOLDER AND ASH RECEPTACLE

Application filed June 29, 1928. Serial No. 289,153.

This invention relates generally to smoker's articles, and has more particular reference to a safety pipe for smoking cigarettes or the like.

5 The invention has for an object the provision of a device of the class mentioned, which is of simple durable construction, desirable and efficient in action, and which can be manufactured and sold at a reasonable 10 cost.

The invention proposes the use of a tubular member arranged for holding a stem adapted to hold a cigarette within the tubular member. An ash receptacle is attached 15 to the tubular member which is provided with openings for permitting cigarette ashes to fall into the receptacle. The receptacle is provided with a door thru which the ashes may be removed. A tubular 20 match holder, and scraper holder is insertable into the said tubular member for normally closing the aperture communicating with the ash receptacle for permitting the device to be carried in one's pocket without 25 spilling the ashes from the receptacle. The device may be provided with a slide for this same purpose.

For further comprehension of the invention, and of the object and advantages there- 30 of, reference will be had to following description and accompanying drawings, and to the appended claims in which the various novel features of the invention are more particularly set forth.

35 In the accompanying drawing forming a material part of this disclosure,

Fig. 1 is a perspective view of a device constructed according to this invention.

Fig. 2 is an end view thereof, looking 40 from the stem end of the device.

Fig. 3 is a plan view of the device with the tubular match holder removed.

Fig. 4 is a perspective view of the scraper, per se.

45 Fig. 5 is a perspective view of the tubular match holder, per se.

Fig. 6 is a fragmentary perspective bottom view of the ash receptacle.

Fig. 7 is a fragmentary central vertical 50 sectional view of an ash receptacle of modi-

fied form.

Fig. 8 is a transverse vertical sectional view as though taken on the line 8—8 of Fig. 3, but illustrating a modified form of the device.

Fig. 9 is a plan view thereof.

The reference numeral 10 indicates generally a tubular body member having an elongated top aperture 11 covered by a screen 11' and a smaller elongated bottom aperture 12. A stem 13 is screwed into one end of the tubular body member, and is adapted for holding a cigarette so that it extends thru the tubular body member and between the apertures 11 and 12. An ash container 14 is secured to the bottom of the member 10, and has an open top aligned with opening 12, and a removable bottom 15 held in place by a screw 16.

A tubular match holder 17 has a cap 18 screwed on one end, and the other end, is adapted to receive the screw portion 19 of the head 20 of a scraper 21 so that this scraper may be housed within the holder 17 also.

A hinged cap 10^a is provided at the end of the tubular body 10 at the end opposite to the stem 13 and the said cap is provided with a metal screen 11^a to prevent the burning tobacco from falling out of the tubular holder. The cap 10^a is locked to the tubular body member 10 by any suitable catch 10^c. This arrangement makes my device fire- 85 proof.

Normally when the device is carried in one's pocket, the match holder 17 is engaged into the tubular body member 10 thru its open end as shown in Fig. 1. In this condition of the device cigarette ashes contained in the receptacle 14 cannot be spilled into the said pocket thru the opening 12. For using the device during smoking, the match holder 17 is first removed from the body 10, then the stem is removed and a cigarette engaged in the stem which is next reengaged in the body 10. The cigarette may then be lit, and the burnt match inserted in the member 17 by way of the removable cap 18.

As the cigarette is smoked ashes there- 100

from will fall thru the aperture 12 into the container 14. During smoking the device can be conveniently rested upon a table or the like. Upon completion of smoking the cigarette, the butt thereof may also be deposited into the ash receptacle by removing the same from the stem, use being made of the scraper 21 for this purpose. The scraper may also be used for scraping charrings 10 from the inner side of the body 10.

The modified form of the device illustrated in Fig. 7 discloses a bottom cover 15' hingedly connected to one edge of the receptacle, as at 22 and normally held closed by a spring pressed pin 23 engaging in an eye 24 secured to the cover 15'. When the head of the pin 23 is drawn outwards, the cover 15' opens as indicated by dot dash lines 25, for emptying the ashes therefrom.

In Figs. 8 and 9 another modification has been shown in which the tubular body member 10' is formed with a slot 26 for supporting a slide 27 which has a knob 28 on its outer edge. In retracted position this slide 25 closes aperture 12 for preventing a spilling of the ashes within the receptacle. Springs 29 attached on the outside of the container 14 press against the outer edge of the slide for holding the slide in retracted position. These springs may be turned about pivots 30 for disengaging the slide which can then be extended to a position as limited by the downturned inner edge 31 thereof.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:

1. A device of the class described, comprising a tubular body member formed with a top and a bottom elongated aperture, a screen covering the top opening, a cigarette holding stem removably engaged in one end of the said tubular member, an ash receptacle attached to the tubular member and having an open top aligned with one of the said apertures for receiving ashes from burning cigarettes disposed within the tubular body, and a tubular burnt match holder disposed 110 with the tubular body for simultaneously holding burnt matches and closing the entrance opening to the ash receptacle.

2. A device of the class described, comprising a tubular body member formed with a top and a bottom elongated aperture, a screen covering the top opening, a cigarette holding stem removably engaged in one end of the said tubular member, an ash receptacle attached to the tubular member and having an open top aligned with one of the said

apertures for receiving ashes from burning cigarettes disposed within the tubular body, and a tubular burnt match holder disposed with the tubular body for simultaneously holding burnt matches and closing the entrance opening to the ash receptacle, said match holder being provided with an end removable cap. 70

3. A device of the class described, comprising a tubular body member formed with a top and a bottom elongated aperture, a screen covering the top opening, a cigarette holding stem removably engaged in one end of the said tubular member, an ash receptacle attached to the tubular member and having an open top aligned with one of the said apertures for receiving ashes from burning cigarettes disposed within the tubular body, and a tubular burnt match holder disposed with the tubular body for simultaneously holding burnt matches and closing the entrance opening to the ash receptacle, said match holder being provided with an end removable cap and with a scraper. 75 80

4. A device of the class described, comprising a tubular body member formed with a top and a bottom elongated aperture, a screen covering the top opening, a cigarette holding stem removably engaged in one end of the said tubular member, an ash receptacle attached to the tubular member and having an open top aligned with one of the said apertures for receiving ashes from burning cigarettes disposed within the tubular body, and a slide mounted in the tubular body member and arranged for normally closing the entrance opening of the ash receptacle. 90 95 100

In testimony whereof I have affixed my signature.
